UNITED STATES PATENT OFFICE

ALFRED WEINSTEIN, OF HAMBURG, GERMANY

ANIMATED DEVICE

Application filed April 23, 1929. Serial No. 357,509.

This invention relates to animated devices, and pertains more particularly to devices of this character which include scenes having movable propellers, vanes, rotors, or the like.

One feature of the invention is the provision of a device of the character mentioned in which improved means is provided to cause displacement or rotation of the movable elements.

Another feature is to provide a structure dependent on manual operation for causing such displacement or rotation.

With these and other advantageous features in view, the invention comprises various novel features of construction and arrangements of parts which will be more fully described hereinafter and set forth with particularity in the claims appended hereto.

20 In the accompanying drawings,

Figure 1 is an elevation of an animated device.

Figure 2 is a vertical section thereof, on line 2—2 of Figure 1.

25 Figures 3, 4, and 5 are details of the propeller and the propeller mounting.

Referring to Figures 1 and 2 of the drawings, a front plate or card 10 depicts a scene having a displaceable element therein.

30 The plate has an opening 11 in the region of the displaceable element, a second plate 12 being affixed contiguous to the plate 10, by means of glue or the like, and bearing a complementary representation to the scene

35 depicted on plate 10 on that portion adjacent the opening 11. Mounted in said opening is a transparent cup or the like 13, preferably of celluloid, a flange 14 being secured between the two plates. Within the cup 13 is a displaceable element, in the present disclosure a propeller or rotor 15 is shown, preferably as having a plurality of

40 blades 16, attached to a bearing element 17, a flange 18 thereon serving to maintain the upright position of the propeller or rotor.

45 The bearing element 17 is rotatably mounted on a shaft 19, having a base member 20, the shaft 19 extending through the plate 12, and the base 20 being affixed to the plate 12 by glue or other means. As will be noted from

Figure 2, the bearing element 17 and the propeller mounted thereon, are free to rotate on the shaft 19, the bearing element also functioning as a spacer to prevent displacement from the shaft.

55 A third plate or card 21 is affixed to the other plates preferably at the edges thereof, and is normally held spaced from said other plates at its middle portion by a spring 22 so as to obtain a bellows action when the plates are pressed toward each other. An air directing nozzle 23, or the like is formed in plate 12 adjacent the propeller 15, so positioned as to cause the air current generated by the bellows action of said plates 60 to impinge against the arms of the rotor at a point to one side of its center to operate the same at a high velocity if desired and an opening 24 is provided in the side of cup 13, to permit flow of air.

65 The operation of the improved device is as follows: A manual displacing of the plate 21 toward the other plates, against the force of the spring 22, causes a flow of air through the nozzle opening 23 to impinge on the blades 16, to one side of its center the air then passing out through opening 24. As the plate 21 is allowed to move back, the air flows back, so that an additional displacement of plate 21 causes a further rotation of the rotor 70 but it is found that this action of the air from the bellows will operate the rotor even though this opening 24 is closed.

75 The advantageous features of the device will be readily understood from the foregoing description taken in connection with the accompanying drawings; and while I have described one specific embodiment thereof, I desire to have it understood that the device shown is merely illustrative, and that such 80 changes may be made as are within the scope of the appended claims.

85 I claim:—

1. In an animated device, a plate bearing a representation thereon, a pivot pin fixed on said plate, a member rotatably mounted on said pin and having vanes, a nozzle opening in said plate adjacent said vanes, a transparent cup secured to said plate and covering said member and the nozzle and having an 90 100

opening, and means for forcing air through said nozzle opening to impact on said vanes.

5 2. In an animated device, a plate bearing a representation thereon, a pivot pin fixed on said plate, a member rotatably mounted on said pin and having vanes, a nozzle opening in said plate adjacent said vanes, a transparent cup secured to said plate and covering said member and the nozzle and having an opening, a second plate secured at its edges to the first plate at the rear thereof, and a resilient member normally displacing said second plate from said first plate.

10 3. In an animated device, a plate bearing a representation thereon, an opening therein, a second plate secured to said plate and bearing a complementary representation adjacent said opening, a pivot pin fixed on said second plate within said opening, a member having vanes rotatably mounted on said pivot pin, a nozzle opening in said second plate adjacent said vanes, a transparent cup secured to said second plate and covering said member and the nozzle and having an opening, a third plate positioned in rear of said second plate and secured to said first plate at the edges thereof, and a spring normally displacing said third plate from said first and second plates.

15 30 In testimony whereof I affix my signature.
ALFRED WEINSTEIN.
